UNITED STATES PATENT OFFICE.

HERMAN C. DOMAN, OF OSHKOSH, WISCONSIN.

WASHING MACHINE.

1,422,547.

Specification of Letters Patent. Patented July 11, 1922.

Application filed August 5, 1919. Serial No. 815,480.

To all whom it may concern:

Be it known that I, HERMAN C. DOMAN, a citizen of the United States, and resident of Oshkosh, in the county of Winnebago and State of Wisconsin, have invented new and useful Improvements in Washing Machines, of which the following is a description, reference being had to the accompanying drawings, which are a part of this specification.

10 The present invention relates to certain new and useful improvements in washing machines of that type used in washing wearing apparel and the like.

In the washing machines now in common everyday use, a reciprocating and oscillating "dolly" is employed which has proven very unsatisfactory in that it is practically impossible to use the same in connection with fine materials as the "dolly" often tears

20 the clothing.

Hence with these inherent objections in mind, my invention has for one of its objects to provide a washing machine in which a plurality of spray nozzles are employed, so arranged as to direct a spray of fluid therefrom in a direction to impart to the clothes, within the washer, a whirling movement.

Another object of the present invention is to provide a washing machine of the class 30 described employing a plurality of spray nozzles so arranged as to impart a whirling movement to the clothes being cleaned in which the spray from the nozzles will be of sufficient strength to loosen the dirt from 35 the clothes.

A further object of this invention is to provide means for selectively supplying fluid to a plurality of spray nozzles so arranged as to impart a whirling movement to 40 the clothes being cleaned.

A still further object of this invention is to provide means for circulating the water in the washing machine through the cleansing spray nozzles.

45 A still further object of the present invention is to provide a cylinder having a reciprocating piston therein arranged to draw the water from the washing machine container to force the same through one of a 50 plurality of spray nozzles arranged to discharge within the container of the washing machine, and means operable upon one complete movement of the reciprocating piston to connect the discharge port of the cylinder with another spray nozzle of the plurality.

With the above and other objects in view which will appear as the description proceeds, my invention resides in the novel construction, combination and arrangement of 30 parts substantially as hereinafter described and more particularly defined by the appended claims, it being understood that such changes in the precise embodiment of the hereindisclosed invention may be made as 35 come within the scope of the claims.

In the accompanying drawings I have illustrated one complete example of the physical embodiment of my invention constructed according to the best mode I have 70 so far devised for the practical application of the principles thereof, and in which:

Figure 1 is a view part in section and part in elevation of a washing machine embodying the several features of my invention. 75

Figure 2 is a top plan view of the washing machine container, said container being shown with the usual cover removed therefrom.

Figure 3 is a detailed sectional view 80 through the novel form of rotary valve employed to selectively connect the spray nozzles with the fluid supplying cylinder, said view being taken on the line 3-3 of Figure 1. 85

Figure 4 is an elevational view of the supplying cylinder, piston reciprocating means and rotary valve operating means, said view being taken looking at the side of the cylinder to the right with reference to Figure 1, 90 and

Figure 5 is a top plan view of the operating mechanism for the reciprocating piston and selectively rotatable valve, said view being taken on the line 5-5 of Figure 4. 95

Referring now more particularly to the accompanying drawings, the numeral 6 designates the work container or receptacle; 7 the supporting legs for the container 6; and 8 a transverse platform or base for receiving the operating mechanism for supplying water to the interior of the container 6 under pressure.

100 Fixed in the bottom wall 9 of the receptacle or container 6 are a plurality of spaced apart discharge nozzles 10, which have their top portion curved and provided with discharge or spray jets 11, the spray jets being so arranged as to discharge on a line leading to the adjacent spray nozzle, as best shown 110 in Figure 2. Each spray nozzle 10 is connected by means of a pipe 12 with the upper

counter-bored end 13 of a cylinder 14 adapted to be secured centrally to the underside of the bottom wall 9.

Mounted in the counter-bored end 13 is a substantially inverted cup-shaped rotary valve 15 carried by a valve rod or stem 16, journalled at its lower end in the bearing 17 fixed to the base 8. The valve 15 has a single port 18 in its side peripheral wall 5 adapted to be selectively registered with the ends 19 of the pipes 12 communicating with the counter-bored end 13. The valve 15 is rotated to selectively register with said ends 19 by means to be later described. 10

15 Reciprocally mounted within the cylinder 14 is a piston 20, having its rod 21 centrally bored and slidably mounted on the valve stem or rod 16, and having its lower end slidably mounted in a packing gland 20 22, formed centrally on a cap 23, closing the lower end of the cylinder. The lower end of the cylinder is in communication with the container or receptacle 6 by means of a circulating pipe 24 leading from the bottom 25 of the container, as at 25, and connected with the cylinder, as at 26, the end 25 of the pipe being covered by a screening member 27.

The piston 22 is reciprocated, by means 30 to be later described, and in its downward movement a plurality of gravity controlled valves 28 carried thereby are operated to allow the water supplied to its underside by the circulating pipe 24 to pass there- 35 through, and in its upward movement the valves 28 automatically close and the water then on the upper side of the piston is forced through the port 18 of valve 15 and out through the discharge jet 11 of the spray 40 nozzle, having its end 19 registered with the port 18. The piston in its upper movement creates a suction or vacuum on its under side and draws water into the cylinder through circulating pipe 24, in order that 45 in its downward movement there will be water to pass by the valves 28 as before described.

The piston 20 is reciprocated by means 50 of an electrical motor 29 in geared connection with a gear 30 carried by a shaft 31, journalled in bearing 32 and having a crank 33 formed thereon and connected with a lever 34 having one end pivoted, as at 35 to a brace 36 carried by a rear wall of 55 the container 6, by means of a link 37. The other end of the lever 34 is forked to provide a bearing of spaced arms 37' pivotally connected to a cross head or bar 38 carried by the lower end of the piston rod 21. Thus 60 it will be obvious that by the rotation of the crank 33 through the medium of the motor 29, the piston 20 will be reciprocated within the cylinder 14.

The valve 15 is rotated one step upon 65 each working stroke of the piston 20 so

that first one spray nozzle will be coupled with the port 18 upon one upward stroke of the piston, and another upon the next upward stroke of the piston as will be apparent. The means I employ for intermittently rotating the valve 15 one step at a time comprises a ratchet wheel 39 fixed to the valve stem 16 near its lower end and selectively engageable with its teeth 40 is a pivoted pawl or dog 41 carried by a lever 42, having one end freely pivoted on the rod or stem 16 adjacent the ratchet wheel 39, the pawl or dog 41 being normally urged to engage the periphery of the wheel 39 by means of a flat spring 43. The other 70 free end of the lever 42 is pivotally connected with the long arm 44 of a bell crank lever by means of a link 45, having a pivotally connection with the arm 42 and a universal joint connection, as at 46, with the bell crank lever. The bell crank lever is pivoted to a standard 47 carried on the base 8 and has its other shorter arm 48 connected to the lever 34 medially of its ends by means 75 of a pivoted link 49. 80

The bell crank lever 48 is so proportioned and connected with the lever 34 so that when the piston 20 is on its upward movement, the dog or pawl 41 will be moved in an anti-clockwise direction with respect to Figure 90 5 to engage the pawl behind the next tooth 40, as depicted in dotted lines, so that upon its downward movement the pawl 41 will rotate the ratchet wheel one tooth in a clockwise direction to position or register the port 18 with the end 19 of the next spray nozzle. 95

In order to prevent the valve 15 from being rotated in anti-clockwise direction when the pawl 41 is riding over the next tooth, by the friction thereagainst the ratchet wheel caused by its spring 43, I provide a plurality of notches or recesses 50 in the side wall of the valve 15 so arranged that when the port 18 is registering with the end 19 of any one pipe 12, one of the notches 100 will be engaged by a spring operated ball or check 51 carried by the adjacent portion of the counter-bored end 13, as at 52, see Figure 3. 110

The check or ball 51 prevents the accidental movement of the port 18 from registering with its adjacent pipe end 19. 115

As best shown in Figures 1 and 2, the sharp corners of the container 6 are relieved by inclining them, as at 6', so that no resistance will be offered to the clothes in their whirling movement. The jets 11 are so arranged that the sprays 11' ejected therefrom will be upwardly at an angle 120 from the bottom 6 and towards the adjacent spray nozzle 10 whereby a whirling movement will be imparted to the clothes within the container 6 by the sprays 11. The sprays 11' take the place of the reciprocating 125 sprays 11. 130

ing or oscillating "dolly" now generally employed in washing machines and the spray 11' is of sufficient force to play upon the clothes penetrating therethrough, which together with the whirling movement of the clothes thoroughly cleanses the same.

What I claim as my invention is:

1. A washing machine comprising a container, a plurality of spray nozzles located 10 in said container so that the water discharged therefrom will impart a whirling movement to the garments being washed, a source of washing fluid, a pump, and means for intermittently putting said pump into communication with said nozzles one at a time for the purpose described.

2. A washing machine comprising a container, a plurality of spray nozzles in the bottom of said container, said nozzles being 20 arranged so that the respective jets discharge therefrom upwardly at an incline and in a direction toward the adjacent nozzle so that a whirling movement is imparted to the garments being washed, a source of washing 25 fluid, a pump, and means for intermittently putting said pump into communication with said nozzles one at a time for the purpose described.

3. A washing machine comprising a container, a plurality of spray nozzles in the bottom of said container, said nozzles being arranged so that the respective jets discharge therefrom upwardly at an incline and in a direction toward the adjacent nozzle so 35 that a whirling movement is imparted to the garments being washed, a source of washing fluid, a pump, means to operate said pump, a valve adapted to place said pump in communication with said nozzles one at a time, 40 and automatic means for shifting said valve for the purpose described.

4. A washing machine of the class described comprising a container, a cylinder secured to the outside of the container, spray 45 nozzles adapted to discharge within the container and connected with said cylinder, a pipe leading from the container to the lower portion of the cylinder, a piston mounted within the cylinder and adapted to be re-

ciprocated to force water through the spray 50 nozzles and onto the clothes within the container to be cleaned, and means adapted to place said cylinder in communication with said nozzles one at a time.

5. A washing machine comprising a container, a plurality of spray nozzles located in said container so as to discharge thereinto, a cylinder positioned under said container, discharge pipes leading from the upper end of said cylinder to said respective nozzles, a pipe leading from the bottom of said container to the bottom portion of said cylinder, a piston in said cylinder, means to reciprocate said piston, said piston having a one way valve so that during its downward stroke water may pass from the bottom to the upper portion of said cylinder, a valve associated with said discharge pipes and arranged so that water can only flow from said cylinder into one of said discharge pipes at a time, and automatic means for shifting said last mentioned valve for the purpose described.

6. A washing machine comprising a container, a plurality of spray nozzles in the bottom of said container, said nozzles being arranged so that the respective jets discharge therefrom upwardly at an incline and in a direction toward the adjacent nozzle so that a whirling movement is imparted to the garments being washed, a cylinder positioned under said container, discharge pipes leading from the upper end of said cylinder to said respective nozzles, a pipe leading from the bottom of said container to the bottom portion of said cylinder, a piston in said cylinder, means to reciprocate said piston, said piston having a one way valve so that during its downward stroke water may pass from the bottom to the upper portion of said cylinder, a valve associated with said discharge pipes and arranged so that water can only flow from said cylinder into one of said discharge pipes at a time, and automatic means for shifting said last mentioned valve for the purpose described.

In testimony whereof, I affix my signature.
HERMAN C. DOMAN.
